UNITED STATES PATENT OFFICE.

FERDINAND CHARRON AND LÉONCE GIRARDOT, OF PUTEAUX, FRANCE.

EXPLOSION-MOTOR.

SPECIFICATION forming part of Letters Patent No. 761,656, dated June 7, 1904.

Application filed March 3, 1903. Serial No. 145,970. (No model.)

To all whom it may concern:

Be it known that we, FERDINAND CHARRON and LÉONCE GIRARDOT, citizens of the Republic of France, and residents of 7 Rue Ampère, 5 Puteaux, Seine, in the Republic of France, have invented certain new and useful Improvements in Explosion-Motors, of which the following is a specification.

This invention relates to improvements in 10 explosion-motors, petrol-motors, and the like for the purpose of producing motors of great lightness, constructed entirely of steel, and easy to mount and to inspect.

The improvements relate more particularly 15 to the construction and arrangement of the cylinder and the valve-boxes, to the mounting of the said boxes and their closing-plugs, and to the means of fixing to the various parts of the motor a thin metal casing or jacket intended to form a water-chamber.

In the accompanying drawings, Figure 1 is 20 a vertical section of the motor in a plane passing through the valve-boxes. Fig. 2 is a plan view. Fig. 3 is an elevation; and Figs. 4, 5, 25 and 6 represent, on a smaller scale, an elevation, a plan view, and a vertical section, respectively, of the motor-cylinder, the vertical section being on the line 1 2 of Fig. 5. Fig. 7 is a detail sectional view of the closing device 30 of the valve-boxes at an enlarged scale, and Fig. 8 is a section made through line A B of Fig. 7.

The cylinder is formed of a bored and polished block of cannon-steel, so that the walls 35 can be of very slight thickness, owing to the strength of the metal. The cylinder can also be made of cast-steel. This cylinder *a* is only open at the base and is provided at the latter with a flange for fixing it to an ordinary frame 40 *b*. At its upper end it has a cover *c*, integral with the lateral walls, and two cylindrical bosses *d* and *e*, diametrically opposite each other, with screw-threaded outer surfaces. In order to utilize to the fullest possible extent 45 the total height of the cylinder and to avoid useless weight, the cover *c* has a semicylindrical bore in line with the bosses *d* and *e*, and externally the cover is recessed in such a manner that its thickness is approximately uni-

form in all its parts. The cylinder thus obtained is extremely light in proportion to the power which can be developed in it.

The valve-boxes are of cast-steel. One is provided for supply and one for exhaust. These valve-boxes are identical in construction and interchangeable. Each valve-box is provided with a screw-threaded boss *f*, adapted to be screwed to one of the bosses *d* and *e* of the cylinder. The joint produced by the screwing alone is sufficiently tight; but it can be rendered more perfect in a simple manner without inserting any special part. For this purpose it is sufficient to construct the bosses *d* and *e* with small flanges *g*, Fig. 1, round their inner circumference, to provide corresponding recesses *h* in the valve-boxes, and then to expand the flanges *g* after the valve-boxes have been screwed to the cylinder. This is rendered possible by means of apertures in the walls of the valve-boxes opposite 70 the bosses *f*. The aperture in the wall of the supply valve-box serves to receive the ignition-tube *i*, and the aperture in the wall of the exhaust valve-box is closed by means of a screw-stopper *j*. The valve-boxes are 75 also provided with apertures for the supply-pipe *k* and exhaust-pipe *l*, respectively, and for the valve-rods. In the upper parts of the valve-boxes apertures *m*, with plugs or covers *n*, are provided to give access to the valves. 80 The removal of the said screw-covers is very easy and can be effected instantaneously. For this purpose a collar *n*, with two projecting knob-headed studs *o* and *p*, is adapted to be screwed fixedly to the flange surrounding 85 the aperture *m*. A cross-bar *q* is connected by a screw *r* at its center with the cover or plug *n*, as shown in Fig. 1. The ends of the cross-bar *q* are adapted to engage the studs *o* and *p*, respectively. If the screw *r* is screwed downward while the cross-bar is in engagement with the said studs, the screw presses the plug or cover firmly onto its seat and makes a gas-tight joint. For removing the plug it is sufficient to loosen slightly the screw *r* and 90 then rotate the cross-bar out of engagement with the studs *o* and *p*, whereupon the said bar need only be lifted in order to remove

the plug, the latter being connected to the cross-bar by means of the screw r and a nut r' , engaging a plate v' , fixed to the plug.

The casing which surrounds the cylinder 5 and the valve-boxes and in which the cooling-water circulates consists of a copper jacket fixed at its lower end directly to the circumference of the cylinder and at its upper end to the valve-boxes. This jacket is preferably 10 T-shaped and arranged with its vertical part t surrounding the body of the cylinder and its horizontal part u surrounding the upper end of the cylinder-bottom and the valve-boxes. The part u is not cylindrical, but has 15 a flattened upper surface. This jacket u is provided with openings for the valves and valve-rods and the like and is soldered or otherwise fixed to the cylinder and the valve-boxes at the parts marked s in Figs. 1 and 2. 20 The two valves x and y for supply and exhaust, respectively, are automatically operated by cams 1 and 2, fixed at an angle of one hundred and eighty degrees to each other to parallel shafts 3 and 4, respectively. The 25 said shafts 3 and 4 revolve with equal speed and are driven by the main shaft 5 by means of gear-wheels. The rods 7 and 8, which the said cams operate, have rollers 9 and 10 at their lower ends and are guided in vertical 30 tubes, as shown in the drawings.

In using this type of motor with motor-cars several coupled cylinders will preferably be employed, more particularly four cylinders placed in line, with their pistons acting on 35 the same shaft. The cam-shafts will in this case be common to all the cylinders, and a common feed and exhaust pipe will be provided.

Having now described our invention, what 40 we claim as new, and desire to secure by Letters Patent, is—

1. An explosion-motor, comprising a hollow steel cylinder a open at one end, two hollow lateral screw-threaded bosses d e at its upper 45 end, the said bosses being diametrically opposite each other and integral with the cylinder, and a flange g at the end of each of the said bosses, in combination with two cast-steel valve-boxes identical with each other, a hollow screw-threaded boss f cast with each valve-box adapted to be screwed to one of the bosses d and e of the cylinder, a recess h in each of the bosses f , and an aperture in the wall of

each of the said valve-boxes, opposite the respective boss f , substantially as and for the 55 purpose set forth.

2. An explosion-motor comprising a hollow steel cylinder a open at one end, two hollow lateral screw-threaded bosses d e diametrically opposite each other at the upper end of the 60 cylinder and integral with the latter, and a flange g at the end of each of the said bosses e and d , in combination with two cast-steel valve-boxes identical with each other, a screw-threaded tubular boss f on each of the said 65 valve-boxes adapted to be screwed to the corresponding boss of the cylinder, a recess h in each of the bosses f , an aperture in the wall of each of the said valve-boxes opposite the 70 respective boss f , an aperture m in the upper part of each of the said valve-boxes, a collar n adapted to be screwed to a flange surrounding the said aperture m , two knob-headed studs o and p fixed to the said collar n , a cross-bar q with slotted ends adapted to engage the 75 said studs in opposite directions, a fixing-screw r engaging the said cross-bar q and a plug v connected to the screw r , substantially as and for the purpose set forth.

3. An explosion-motor comprising a hollow 80 steel cylinder a open at one end, two hollow lateral screw-threaded bosses d e diametrically opposite each other at the upper end of the cylinder and integral with the latter, and a flange g at the end of each of the said bosses, 85 in combination with two cast-steel valve-boxes identical with each other, a hollow screw-threaded boss f on each of the said valve-boxes, adapted to be screwed to the corresponding boss of the cylinder, a T-shaped tubular jacket 90 of thin sheet-copper, surrounding the upper part of cylinder and the valve-boxes, a vertical part t of the said jacket soldered or otherwise fixed to the lower part of the wall of the steel cylinder itself and a horizontal part u of the said jacket soldered or otherwise fixed to the circumferences of the valve-boxes, substantially as and for the purpose set forth.

In witness whereof we have hereunto set our hands in presence of two witnesses.

FERDINAND CHARRON.
LÉONCE GIRARDOT.
